UNITED STATES PATENT OFFICE.

CLAUDE D. MABERRY AND SAMUEL C. KITTERMAN, OF PARSONS, KANSAS.

ATTACHMENT FOR TRACTION-ENGINES.

1,233,797.

Specification of Letters Patent. Patented July 17, 1917.

Application filed August 2, 1916. Serial No. 112,816.

To all whom it may concern:

Be it known that we, CLAUDE D. MABERRY and SAMUEL C. KITTERMAN, citizens of the United States, residing at Parsons, in the county of Labette and State of Kansas, have invented certain new and useful Improvements in Attachments for Traction-Engines, of which the following is a specification.

10 This invention relates to attachments for traction engines propelled by steam, gasoline, or other types of engines and it is the aim of the invention to provide an attachment which may be readily assembled with 15 the ordinary traction engine and which will prove highly useful in hoisting, pulling, lifting or otherwise moving objects, as for example oil-well casings, pump lines, pump rods, etc.

20 The invention has in view the production of an attachment for the purpose stated which may be readily controlled and which will be adapted to be driven from the engine shaft of the tractor and which will embody means whereby the speed at which the winding drum of the attachment is rotated may be varied to suit the operator of the machine.

Another aim of the invention is to provide 30 means whereby the cable wound upon the said drum may be quickly unwound therefrom and wound thereon at any desired rate of speed.

Another aim of the invention is to provide 35 novel means for bracing the attachment with relation to the frame of the tractor.

In the accompanying drawings:

Figure 1 is a side elevation of the attachment embodying the present invention mounted upon a traction engine of a well known type;

Fig. 2 is a top plan view of the attachment applied;

Fig. 3 is a perspective view illustrating the manner of mounting the shaft from which power is to be applied to the winding drum for the purpose of unwinding the cable therefrom;

Fig. 4 is a vertical sectional view illustrating the manner in which the structure

shown in Fig. 3 is mounted for shifting movement so that it may be thrown into and out of operation;

Fig. 5 is a perspective view of one of the devices provided for bracing the frame of the attachment with relation to the frame of the tractor.

Corresponding and like parts are referred to in the following description and indicated in all the views of the accompanying drawings by the same reference characters.

The traction engine is indicated in general by the reference character T and the frame of the said engine includes side frame members indicated by the numeral 1, these frame members being diverged near their forward ends as indicated by the numeral 2 and thence extended directly forwardly as indicated by the numeral 3, they being supported at their forward ends by the forward wheels 4 of the traction engine and at their rear ends by the rear wheels 5. As the traction engine itself does not enter into the present invention further description thereof is unnecessary except to state that the engine proper may be of any ordinary type, the engine shaft being indicated by the numeral 6 and the fly wheel by the numeral 7.

The attachment embodying the present invention includes two side frame members preferably in the nature of I-beams indicated by the numeral 8, these I-beams being disposed at their rear portions upon the upper sides of the forwardly extending portions 3 of the frame members of the traction engine and being secured by bolts or rivets as indicated by the numeral 9. In order that the frame of the attachment may be braced with relation to the frame of the tractor and in order that the frame members 8 may be braced with relation to each other, a cross piece 10 extends between the frame members 8 near their rear ends and supports uprights 11 to each of which is connected the rear end of a truss rod 12, the forward end of each rod being secured as at 13 to the frame member 8 at the respective side of the attachment. A truss rod 14 is secured at its forward end to the upper end of each of the uprights 11 and these

truss rods are secured at their rear ends as at 15 to the diverging portions 12 of the side members of the frame of the tractor.

Mounted in suitable bearings 16 supported upon the side members 8 near their forward ends are the trunnions of a winding drum indicated by the numeral 17 and one of these trunnions extends beyond its bearing and has fixed thereon a sprocket gear 18 over which is passed a sprocket chain 19. The chain 19 passes also over a sprocket gear 20 fixed upon a shaft 21 which is mounted in suitable bearings 22 upon the side members 8 rearwardly of the winding drum and adjacent the rear ends of the said members 8. A sprocket gear 23 is also fixed upon the shaft 21 beside the gear 20 and trained thereover is a sprocket chain 24 this chain passing also over the gear 25 which is loosely mounted upon the engine shaft at the corresponding side of the frame and beside the fly wheel 7. The numeral 26 indicates a brake drum, and arranged within this drum and designed to clutch the sprocket 25 with the engine shaft is a suitable clutch indicated in general by the numeral 27. Inasmuch as this clutch may be of any of the ordinary types it will not be specifically illustrated nor described. However, the arms which lead from the members of the clutch and which are indicated by the numeral 28 are connected to the intermediate portion of an operating lever 29 which at its forward end is pivoted as at 30 to a bracket 31 secured upon the portion 2 of the corresponding one of the side members 1 of the frame of the tractor. As shown in the drawings the lever 29 extends rearwardly in convenient position for operation by the workman in charge of the machine.

It will now be understood that when the lever 29 is swung inwardly so as to clutch the sprocket gear 25 with the engine shaft, and the engine is in operation, power will be transmitted through the gearing above described to the winding drum 17 and the winding cable which is indicated by the numeral 32 will be wound upon the said drum and will serve to elevate or pull or otherwise act upon the work to be done.

A brake band 33 is applied to the brake drum 26 and the ends of this drum are connected in the ordinary manner with the pivoted end of a lever 34 which lever extends rearwardly and is provided with a foot piece 35 upon which pressure may be applied for the purpose of tightening the band about the drum. In this manner therefore the operator of the machine may control the speed of rotation of the winding drum 17 and consequently the speed at which the cable is wound thereon.

In order that the winding drum 17 may be rotated in a reverse direction for the pur-

pose of unwinding the cable 32, means is provided which will now be described. Fixed upon that end of the shaft 21 opposite the end which carries the sprocket gears 20 and 23, is a pulley 36 over which is passed a belt 37 this belt passing also over a smaller pulley 38 fixed upon one end of the shaft 39. The shaft 39 is mounted in suitable bearings 40 upon a bed piece 41 which is disposed to rest upon the portions 2 of the side members 1 of the tractor frame and in order that the bed piece may be supported in such manner as to permit of its being swung slightly for a purpose to be presently explained, a swivel bolt 42 is fitted through the bed piece 41 and through that one of the side members 2 adjacent that end of the shaft upon which the pulley 38 is fixed. Upon the other end of the shaft 39 there is fixed a wheel having a friction peripheral surface, this wheel being indicated by the numeral 43 and the said wheel is located immediately in advance of and close to the fly wheel 7. It will now be understood that when the clutch 27 is out and the sprocket gear 25 is disconnected from the shaft 6, the bed piece 41 may be swung rearwardly in order to bring the periphery of the wheel 43 into contact with the periphery of the fly wheel of the engine whereby power will be transmitted through the belt gearing just described and through the sprockets 18 and 20 and chain 19 to the drum 17 rotating the said drum in a direction the reverse of that in which it is rotated through the gearing first described. It will also be understood that after the cable has been paid out the desired length, the bed piece 41 may be swung forwardly so as to bring the wheel 43 out of contact with the fly wheel 7 thereby stopping the rotation of the drum. In order that the bed piece may be shifted in the manner stated an arm 44 extends from the free or last mentioned end thereof laterally and has pivotally connected to it, as at 45, an operating rod 46 provided at its rear end with a handle 47 which may be grasped for the purpose of shifting the rod in forward or rear direction for the purpose of swinging the bed piece. In order that the operating rod 46 may be so supported as to at all times be in convenient reach of the operator and so that he may if desired simultaneously operate the lever 29 and rod 46 in a convenient manner, the said lever 29 is provided with an up-standing bracket arm 48 having at its upper end a bearing portion 49 through which the rod 46 may readily slide. It will be understood that swinging movement of the lever 29 will in no way disturb the adjustment of the bed piece 41 inasmuch as the rod 46 is free to slide through the bearing portion 49 and is pivoted at its forward end to the arm 44.

In order that the forward end of the at- 130

tachment may be securely anchored so as to compensate for lateral strain, a clevis 50 is secured upon the forward end of each of the side members 8 and a chain 51 is connected to each of these clevises and is provided with one or more hooks or other suitable securing or attaching elements 52 which may be connected in any suitable manner with any suitable anchoring means.

Having thus described the invention what is claimed as new is:

1. The combination with an engine shaft and the fly wheel thereof, of a winding drum, a shaft geared with the said drum, 15 a gear loose upon the engine shaft and geared with the second mentioned shaft, means for clutching the said gear with the engine shaft, a support mounted at one end for swinging movement, a shaft mounted 20 upon the support, gear elements upon the second and last mentioned shafts operatively connected in a manner to permit of swinging of the support, a friction wheel upon the last mentioned shaft at the end corresponding to the outer end of the said support, and means for swinging the support to position the friction wheel in and out of gear with the fly wheel.

2. In an attachment of the class described, 30 the combination with the frame of a tractor, of frame members mounted thereon and ex-

tending beyond the said tractor frame, a cross member extending between the said frame members and relatively bracing the same, standards upon the cross member, 35 truss rods connected to the standards and to the said frame members, and other truss rods connected to the standards and to the frame of the tractor, the two sets of truss rods extending in opposite directions. 40

3. The combination with an engine shaft and the fly wheel thereof, of a winding drum, a gear element loose upon the shaft and geared with the said drum, means for clutching the gear element with the shaft, 45 an operating lever for the said means provided with an upstanding bracket portion having a bearing part, a shiftable support, a shaft mounted thereon and geared with the said winding drum, a friction wheel upon 50 the last mentioned shaft adapted upon shifting of the said support to be brought into and out of gear with the fly wheel, and an operating member connected with said support and freely slidably through and supported by the bearing part of the upstanding bracket member upon the operating lever for the clutch.

In testimony whereof we affix our signatures.

CLAUDE D. MABERRY. [L. S.]
SAMUEL C. KITTERMAN. [L. S.]
